A. M. DEMUTH

CONDENSER

Filed August 17, 1925

Fig. 1

Patented Apr. 13, 1926.

UNITED STATES PATENT OFFICE.

ALFRED M. DEMUTH, OF CHICAGO, ILLINOIS.

CONDENSER.

Application filed August 17, 1925. Serial No. 50,636.

To all whom it may concern:

Be it known that I, ALFRED M. DEMUTH, a citizen of the United States, residing at Chicago, in the county of Cook and State 5 of Illinois, have invented certain new and useful Improvements in Condensers, of which the following is a specification.

This invention relates to improvements in condensers, particularly adapted though not necessarily limited in its use with cooking apparatus in which the food is cooked under steam pressure and from which cooker the steam or vapor is allowed to escape after the completion of the cooking 15 operation.

The escaping steam contains some of the by-products of the food and by discharging such steam into this improved condenser, the steam will be condensed and the by-products will be saved. Furthermore it avoids the necessity of allowing the steam to escape into the room.

A further object is to provide an improved condenser of this character having 25 mechanical means for inducing a circulation of the cooling air therethrough.

A further object is to provide an improved condenser of this character which will be compact and simple in construction 30 providing a maximum area of cooling surface against which the steam or vapor and the cooling air circulate.

To the attainment of these ends and the accomplishment of other new and useful 35 objects as will appear, the invention consists in the features of novelty in substantially the construction, combination and arrangement of the several parts hereinafter more fully described and claimed and as shown 40 in the accompanying drawing and in which drawing,

Figure 1, is a vertical sectional view of a condenser of this character constructed in accordance with the principles of this invention.

Figure 2, is a horizontal sectional view on line 2—2 Figure 1.

Referring more particularly to the drawing the numeral 10 designates a cylindrical outer shell or casing having a top 17 and a bottom 19 spaced a considerable distance above the lower end 20 of the said casing.

An inner shell 16 of smaller diameter than the outer shell is concentrically located 55 within the upper end of the outer shell so as to form a cylindrical chamber 11 between

the bottom of the two shells and an annular chamber 14 between the two shells.

Arranged within the chamber 11 and opening through the bottom 19 of the outer shell and the bottom 15 of the inner shell are a plurality of air circulation pipes or tubes 21 for conducting atmospheric air into the inner shell 16 and from which latter the air will pass out through openings 18 in the top 17.

The entire structure thus described may be supported in any suitable manner preferably by means of legs or supports 22 to hold the bottom 20 of the outer shell above the floor so as not to interfere with the circulation of air into the tubes or pipes 21. The exterior diameter of the tubes 21, any number of which may be provided is considerably less than the interior diameter of the shell 10 to permit of a circulation of steam or vapor within the shell and adjacent the tubes.

A steam delivery pipe 23 extends through the top 17, and through the inner shell 16 and opens into the outer shell 11 through the bottom 15 of the inner shell for conveying through the inner shell 16 and into the chamber 11, the steam or vapor to be condensed. The pipe 23 may be of any desired 85 diameter but is considerably smaller than the interior diameter of the shell 16. To this pipe 23 may be connected the steam or vapor supply pipe.

If desired a relief valve 24 of any desirable or suitable type may be provided which has communication with the annular chamber 14 to relieve the pressure in the condenser or for permitting vapor to escape 95 therefrom when desired.

The opening into which the valve 24 is secured may be of any desired diameter to afford a cleanout opening when the valve 24 is detached.

A drawoff pipe 25 may be provided which leads through the bottom of the outer shell and a faucet or cock 26 may be connected with the pipe 25 and arranged in a convenient position for the operator.

In use the steam is delivered through the pipe 23 and as it is flowing through the pipe and into the outer shell 11, it will be condensed by reason of the fact that air is circulating through the pipes 21 into the inner shell 16, against the pipe 23 and the 105 wall of the shell 16 and out of the openings 18.

The steam or vapor entering the chamber 11 will circulate therein and into the annular chamber 14 and will thus be exposed to or will contact with an extended cooling surface 5 with the result that the steam or vapor will be rapidly condensed.

If desired a motor 27 may be supported by means of a suitable bracket or support 28 beneath the bottom 19 of the outer shell and adjacent the inlet ends of the tubes 21, for operating a fan or air circulating device 29 which latter serves as a means for inducing circulation of cooling air through the pipes 21, inner chamber 16 and out of the openings 18.

While the preferred form of the invention has been herein specifically described, it is to be understood that various changes may be made in the details of construction and 20 in the combination and arrangement of the several parts within the scope of the claims without departing from the spirit of this invention.

What is claimed as new is:

25 1. A condenser embodying a cylindrical outer shell, a top and bottom therefor, the bottom being spaced a considerable distance above the lower end of the said shell, an inner shell of smaller diameter than the 30 outer shell concentrically located within the upper end of the outer shell to form there-with, a cylindrical chamber between the bottoms of the two shells and an annular chamber between the two shells, air circulating 35 pipes within the said cylindrical chamber and opening through the bottoms of both of said shells, a vapor pipe extending through the said inner shell and having communication with the interior of the said 40 outer shell, and a draw off leading through the bottom of the said outer shell, there being air outlet openings through one of the walls of the said inner shell.

45 2. A condenser embodying a cylindrical outer shell, a top and bottom therefor, the bottom being spaced a considerable distance above the lower end of the said shell, an inner shell of smaller diameter than the outer shell concentrically located within the 50 upper end of the outer shell to form there-with, a cylindrical chamber between the bottoms of the two shells and an annular chamber between the two shells, air circulating 55 pipes within the said cylindrical chamber and opening through the bottoms of both of said shells, a vapor pipe extending through the said inner shell and having communication with the interior of the said outer shell,

a draw off leading through the bottom of the said outer shell, there being air outlet openings through one of the walls of the said inner shell, and a removable relief valve having communication with the said annular chamber.

3. A condenser embodying a cylindrical 65 outer shell, a top and bottom therefor, the bottom being spaced a considerable distance above the lower end of the said shell, an inner shell of smaller diameter than the outer shell concentrically located within the 70 upper end of the outer shell to form there-with, a cylindrical chamber between the bottoms of the two shells and an annular chamber between the two shells, air circulating 75 pipes within the said cylindrical chamber and opening through the bottoms of both of said shells, a vapor pipe extending through the said inner shell and having communication with the interior of the said outer shell, a draw off leading through the bottom of the 80 said outer shell, there being air outlet openings through one of the walls of the said inner shell, and means adjacent the inlet end of the said air circulation pipes for inducing a circulation of air through the last said 85 pipe.

4. A condenser embodying a cylindrical outer shell, a top and bottom therefor, the bottom being spaced a considerable distance above the lower end of the said shell, an inner shell of smaller diameter than the outer shell concentrically located within the 90 upper end of the outer shell to form there-with, a cylindrical chamber between the bottoms of the two shells and an annular chamber between the two shells, air circulating 95 pipes within the said cylindrical chamber and opening through the bottoms of both of said shells, a vapor pipe extending through the said inner shell and having communication with the interior of the said outer shell, a draw off leading through the bottom of the said outer shell, there being air outlet openings through one of the walls of the said inner shell, and mechanical means 100 therefor disposed within the confines of the said outer shell and adjacent the inlet end of the said air pipes for inducing a circulation of air therethrough and through the said inner shell.

In testimony whereof I have signed my name to this specification, on this 15th day of August, A. D. 1925.

ALFRED M. DEMUTH.
